[57] CLAIM

The ornamental design for a shaft housing with integral trough seal, as shown and described.

DESCRIPTION

FIG. 1 is a perspective view of a shaft housing with integral trough seal showing my new design;

FIG. 2 is a typical side elevational view;

FIG. 3 is a bottom plan view;

FIG. 4 is a top plan view;

FIG. 5 is a left side elevational view;

FIG. 6 is a typical side elevational view;

FIG. 7 is a right side elevational view;

FIG. 8 is a typical side elevational view of a second embodiment showing my new design of FIGS. 1-7;

FIG. 9 is a top plan view;

FIG. 10 is a bottom plan view;

FIG. 11 is a left side elevational view; and,

FIG. 12 is a right side elevational view thereof.

The broken line showing of a pipe element is for environmental purposes only and form no part of the claimed design.
